(57) **CLAIM**

The ornamental design for a test meter, as shown and described.

DESCRIPTION

FIG. 1 is a perspective view of the test meter having a transparent cover;

FIG. 2 is a front elevational view of the test meter;

FIG. 3 is a rear elevational view of the test meter;

FIG. 4 is a left side elevational view of the test meter;

FIG. 5 is a right side elevational view of the test meter;

FIG. 6 is a top plan view of the test meter;

FIG. 7 is bottom plan view of the test meter;

FIG. 8 is a perspective view of the test meter emphasizing the transparent cover; and,

FIG. 9 is a perspective view of the test meter without the transparent cover.

The broken lines showing various surface details in FIGS. 3–7 are for the purpose of illustration only and form no part of the claimed design.
